H. G. O'NEILL & W. E. PEARSON.

INDIRECT ILLUMINATION.

APPLICATION FILED OCT. 20, 1916. RENEWED AUG. 7, 1917.

1,257,382.

Patented Feb. 26, 1918.

UNITED STATES PATENT OFFICE.

HENRY G. O'NEILL AND WARD E. PEARSON, OF NEW YORK, N. Y.

INDIRECT ILLUMINATION.

1,257,382.

Specification of Letters Patent. Patented Feb. 26, 1918.

Application filed October 20, 1916, Serial No. 126,662. Renewed August 7, 1917. Serial No. 184,975.

To all whom it may concern:

Be it known that we, HENRY G. O'NEILL and WARD E. PEARSON, citizens of the United States, residing at New York city, in the county of New York and State of New York, have invented certain new and useful Improvements in Indirect Illumination, of which the following is a specification.

This invention relates in part to indirect illumination, and in part to direct illumination, preferably by electric lights. The main object of this invention is to obtain an arrangement of indirect or reflected electric or other light rays with a mirror whereby the light rays are reflected on a person to illuminate him as an object before the mirror wherein such person looking into the mirror obtains a reflected image of himself that definitely exhibits features that would not be otherwise clearly and distinctly visible.

We herein describe two different means of effecting the indirect illumination feature of our invention, the first described embodiment of the invention being in the form of a portable electric lamp, and the second described form of the invention relating to a stationary or built-in construction.

In the accompanying drawings forming a part hereof, Figures 1 to 8 are views of a portable electric lamp,

Fig. 1 being a top view of one form of my new lamp, with the case cover closed.

Fig. 2 is a view similar to Fig. 1 except that the case cover is wide open, in which position it can be used for direct illumination.

Fig. 3 is a vertical section through the lamp at line 3—3 of Fig. 5.

Fig. 4 is a plan view of the lamp showing the complementary case members wide open and the cover also wide open.

Fig. 5 is a front elevation of the lamp.

Fig. 6 is a sectional elevation viewed at line 6—6 of Fig. 5.

Fig. 7 is a sectional view at line 7—7 of Fig. 5 showing the cover closed and illustrating one of two devices for holding the complementary hinged case members in closed position.

Fig. 8 is a transverse sectional elevation at line 8—8 of Fig. 1 through the front complementary case member, and particu-

larly illustrates the other of the two locking means for holding the case members closed.

In the drawings, 1 and 2 are sheet-metal case-forming members, each being cupped and fitting together edgewise to form a complete case. Their opposed lower edges are hinged together at 3. The upper end of the closed case is provided with a light-ray exit formed by the edge walls 14, 14 and intermediate back side wall 15 of an integral complementary neck-forming extension of case member 1, and by corresponding edge walls 14, 14 and the intermediate back side wall 15 of an integral complementary neck-forming extension of case member 2. These neck-forming extensions fit together edgewise when the case members 1 and 2 are closed. The open neck thus formed is preferably oblong in cross-sectional contour, and the neck, cross-sectionally considered, is a reduction of the complete case with the opposed intermediate and longer front and back walls 15 parallel with the broader front and back walls of the case members 1 and 2 in order to give a satisfactory amount of reflected light for direct illumination of the user. For the light-ray exit thus provided there is an adjustable cover 4 which near its edges is provided with inwardly-extending parallel ends 5. The rear edge of the cover is hinged at 6 to the back wall 15 of case member 1 which is provided with a transverse fixed lamp-bulb-supporting plate 7, the ends 8 of which are inturned and parallel. Plate 7 is perpendicular to the front and back side walls of the case and is located below the upper edges of the neck-forming extensions. Plate 7 is shorter than the distance between the edge walls 14, 14 of member 1 in order to form two guideways 9 the outward end of each of which is shown at and between an opposed edge wall 14 and the corner formed by the horizontal intermediate plate 7 and one of its inwardly bent ends 8. The ends 5 of cover 4 work into these guideways when the case is closed, the outward surface of each end 5 making frictional contact with a neck wall 14 whereby the ends 5 and walls 14, by thus frictionally contacting, constitute a means for holding the cover shut; and the inner surface of each cover end 5 makes frictional contact with an end 8 of the light-

bulb-supporting plate 7. Such frictional contact also constitutes a further means for holding the cover shut. Plate 7 is wide enough from back to front to form a transverse partition through the closed case, and its rear edge is fixed to case 1. Thus hinge cover 4 may be partially opened and frictionally held in adjusted position at an angle to the axis of the lamp bulb. The cover 10 may be opened full as shown in Fig. 2 for direct lighting as in an ordinary portable electric flash-light, but the partially open position is for indirect lighting and illumination of the user by light rays reflected from 15 the inward face of the cover as a reflector when it is partially open and therefore angularly disposed to the axis of the light-bulb. In this latter position, Fig. 6, the cover ends 5 and neck edge walls 14 form with the cover 20 a sort of hood which is open only at the front so that only the reflected light shines out at the front top end of the case. The electric light bulb 10 is mounted in plate 7 with its outward end below the outward edges of the 25 neck-forming walls 14 and 15. As shown, plate 7 has at its front edge a width sufficient to form a transverse partition for the closed case at the bottom of the neck extension, and has a boss 11 for reception in a 30 hole 12 formed in a spring clip 13 which at one end is secured to case member 2. When the case members are closed, boss 11 and clip 13 become interlocked to hold the case members closed. The clip is provided with an accessible thumb-piece α projecting through a 35 hole in member 2 for disengaging clip 13 from boss 11 when the case is to be opened. For greater security and by preference we provide another spring lock for holding the 40 case members closed and it is formed with a spring arm 16 an end of which is fixed to case member 1, and the bent free end of which extends forwardly to interlock with the bent end of a clip 16^a carried by the front case 45 member 2. Case member 1 is provided with an interior transverse spring plate switch 17 an end of which is fixed to the case member. The bottom electrode of the light bulb is located to make contact with the usual electrode b of the lamp dry-battery B, the usual 50 upstanding electrode b' of which is in the path of a spring switch 17. Case member 1 is provided with a spring clip 18 to hold the battery in place, and with bearings 19 for 55 the bottom and edges of the battery. When cover 4 is closed, and during the closing movement, one of the cover ends engages the free end portion of switch 17, and pressing it out of contact with electrode b' opens the 60 lamp circuit. During the opening movement of the cover, such cover end moves away from the switch, the spring action of which allows it to engage electrode b' to turn on the light. The front edges of the cover ends 5,

5 are cut away (Fig. 6) to permit them to 65 swing into and out of closed position for partially opening the cover when the case members are closed. Preferably case member 2 has a rectangular opening in its front side, and back of this an open-sided box 20 is fixed 70 to form a powder-puff chamber 21 accessible through said front opening which is closed by a mirror-holding frame 22 and the contained mirror, the frame being hinged at 23 to case member 2. The mirror itself is 75 indicated by 24. The chamber-forming box may be omitted if desired, but a mirror located on the front side of the case so as to be used with reflected light from the inner surface of the cover and shining on the user is 80 one feature of this invention. In the construction shown, the mirror frame 22 has an accessible knob 25 for convenience in opening the mirror frame, and the frame has a spring-locking clip 26 a recessed portion of 85 which engages a boss 27 on a wall of the chamber 21 to hold the closure, formed by the mirror frame and mirror, shut. While cover 4 may be partially opened to shed its reflected light as stated, without the use of 90 any positive arresting means, we yet prefer to provide such means, and consequently one of the cover ends 5 is provided with a lug 28 that projects laterally outward and abuts against a case wall, as shown in Fig. 6, when 95 cover 4 has been partially opened into its desired angular position with reference to the axis of the light bulb. To open cover 4 wide, as shown in Fig. 2, when it is desired to use this portable lamp for direct lighting, it is 100 necessary in the construction shown, to first open the front casing; for otherwise the lug 28 would prevent the full opening movement of cover 4.

The advantages of my invention are: simplicity of construction; when the cover of the portable device shown in Figs. 1 to 8 inclusive is lifted into acute-angle light-ray reflecting position, the light may be used to examine a program or the like without throwing light in other directions to the annoyance of others; the cover may be lifted wide open for using the lamp for direct lighting; by gilding the inner face of the cover, the flash-light will emit a softened, pleasing 110 golden glow when the cover is in its light-ray reflecting position; the construction is such that by simply lifting the cover the lamp may be put in circuit and by closing the cover the lamp may be electrically disconnected from 115 the battery,— and hereby we obviate the use of switches that require to be constantly held in position by the user, and also the use of slidable contacts which require to be manipulated to throw on and extinguish the 120 light and which are liable in many positions, as in pockets and in bureau drawers, to become accidentally moved for throwing on 125

the light; and the provision of the powder puff container and mirror adds to the convenience and utility of our new lamp for use by persons attending plays, concerts and the like.

5 What we claim is:

1. The combination of a casing with a self-contained source of direct light; means for turning the light on and off; a reflector hinged to the casing and positionable at an angle to the paths of light rays from such source; and a mirror positioned for observation by a person when illuminated by the reflected light rays; the reflector being provided on its inward side with projecting ends to prevent the light rays from the source of direct light escaping laterally, and one of said ends being provided with a lug adapted to arrest the reflector when raised into an angular position; and within the casing, wall surfaces which frictionally contact with said reflector ends to hold the reflector in its angular position, and an abutment surface against which said lug abuts when the reflector is in its angular position.

2. The combination of a casing having a light-ray exit; a battery, an electric lamp, and electrical connections including a switch between the battery and the lamp, all mounted within the casing; a mirror surface on an outward side of the casing; and a hinged cover for said exit, the cover coöperating with the switch to disconnect the lamp electrically from the battery and being fully openable for direct lighting, and being partially openable to permit impingement of light rays from the electric lamp on the inward surface of the cover as a reflector for indirect illumination of a person when holding the casing in position for observation of his image in the mirror.

3. The combination of a casing having a light-ray exit; a battery; an electric lamp; electrical connections comprising a spring switch between the battery and lamp; and a hinged cover for said exit, the cover comprising a member which on the closing movement of the cover engages the switch to disconnect the battery from the lamp electrically, and the spring action of the switch effecting an electric connection of the battery and lamp during an opening movement of the cover; means for holding the cover in either a closed or partially open position; and abutment members for arresting the opening movement of the cover when it is in an angular position.

4. The combination of a casing having a light-ray exit; a battery, electric lamp, and electric connections comprising switch members between said battery and lamp; a hinged hood-forming cover construction for said exit and constructed to cover the exit except at one space; a mirror on an outward

wall of the casing adjacent said space; and 65 switch-controlling means; the hood-forming cover construction coöperating with wall surfaces within the chamber of the casing for holding the cover closed or partially raised, and comprising a lug adapted to abut with 70 an interior portion of the casing to arrest the opening movement of the cover.

5. The combination of a casing comprising a pair of supplementary hinged members each having a supplementary neck-forming extension open at its outer end; a cover hinged to a free edge of one of the extensions provided with inturned light-excluding ends and dimensioned fully to cover the light-ray exit formed by the complementary neck-forming extensions when they are closed together; a battery detachably mounted in the chamber of the casing; an electric lamp mounted in said chamber; electric connections comprising a switch for 80 the battery and lamp; and an exterior mirror surface on a casing wall adjacent the front edge of the cover; means for holding the cover partially open whereby its inner surface acts as a light-ray reflector; and 90 means for locking the casing members together; the cover having a portion which engages and presses the switch into electrically disconnected position when the cover is closed; and the switch being constructed to throw the switch into electric connecting position when the cover is opened.

6. The combination of a casing comprising a pair of hinged members and having a 100 light-ray exit; means for locking such members together when closed; a demountable battery, and electric lamp; electrical connections comprising a switch for the battery and lamp; and a cover hinged to one of said 105 members and dimensioned to close said opening, the cover comprising a switch-actuating member; each of said members comprising a three-walled neck-extension; a lamp-supporting plate fixed to one of the members 110 and provided with inturned end portions; and the cover having end-forming members constructed and operating frictionally to contact with the inturned end portions of the lamp-supporting plate.

7. The combination of a battery-holding casing having a light-ray exit; an electric light bulb; a supporting plate for the bulb; a battery; electrical connections for the battery and bulb; a spring switch; for said exit 120 a hinged cover constructed and operating to hold the spring switch in electrically disconnected position; and means for holding the cover shut, said means comprising a member carried by the cover and a portion 125 of the plate carrying the electric light bulb.

8. The combination of a battery-holding casing having a light-ray exit; an electric

light bulb; a battery; electric connections for the battery and bulb; and a spring switch; said bulb, battery, electric connections and switch being wholly within the 5 chamber of the casing; and for said exit, a hinged cover provided with a member working within said chamber for engaging the switch to throw it into electrically disconnected position when the cover is shut, the

switch operating by its own spring action to 10 make contact between the lamp and battery; and means for holding the cover shut or partially open, and comprising a lug for arresting the cover in its opening movement.

In testimony whereof we have hereunto 15 set our hands this 18th day of October, 1916.

HENRY G. O'NEILL.
WARD E. PEARSON.
